COOLING UNIT

James H. Kennedy, Evansville, Ind., assignor to
 Sunbeam Electric Manufacturing Company,
 Evansville, Ind., a corporation of Indiana

Application July 16, 1934, Serial No. 735,371
 Renewed February 11, 1938

10 Claims. (Cl. 62—126)

My invention relates to cooling units for use with refrigerators and especially evaporators for use in domestic refrigerators of the type adapted to receive trays for freezing ice, although some 5 of the features of my invention may be incorporated in cooling units involving a brine circulating system.

One object of my invention is a cooling unit which includes a shell and refrigerant-carrying 10 tubing so constructed and arranged as to give an effective cooling action but minimizing irregularities of surface conformation whereby the unit may easily be cleaned.

Another object is a shell and tubing construction for a cooling unit which permits of more effective heat conducting contact between the tray and the tubing.

A still further object of my invention is a simplified but effective release for ice trays which 20 have frozen to their supports.

Another object of my invention is an improved shell and cooling coil therefor to provide localized refrigeration for a tray received by a shelf in the unit.

25 Further objects, features and advantages of my invention are set forth in the following description of specific embodiments thereof which are illustrated in the accompanying drawings, wherein

30 Fig. 1 is an elevation of the left-hand side of a cooling unit in a refrigerator, embodying my invention;

Fig. 2 is a front elevation thereof with the cooling unit door opened;

35 Fig. 3 is a plan section taken on the line 3—3 of Fig. 1;

Fig. 4 is an enlarged detail of the section of a shell including a corrugation therein and a half-round tubing, as shown in Fig. 3;

40 Fig. 5 is a vertical, longitudinal section looking in the same direction as Fig. 1 but taken on the line 5—5 of Fig. 4;

Fig. 6 is a fragmentary, transverse, vertical section taken on the line 6—6 of Fig. 3 looking rearwardly, and

45 Fig. 7 is a fragmentary view similar to the lower portion of Fig. 5 but showing a modification which includes a false bottom for supporting the lower tray.

50 The cooling unit here shown is for use in a domestic refrigerator and it constitutes an evaporator for the refrigerant in connection with a compressor-condenser-evaporator mechanical refrigerating system. The unit is a combined freezing and cooling unit, that is, it is adapted to freeze

water or desserts in freezing trays contained within the shell of the unit while the exterior of the unit is presented to air convection currents for cooling the interior of the refrigerator box.

The cooling unit designated as a whole by the 5 reference character 10 comprises, in general, a shell 11 formed from sheet metal, a header 12 and a plurality of more or less U-shaped lengths of tubing 13 having their ends communicating with the header and received in corrugations 14 in the 10 shell 11.

The shell 11 as here shown is made from sheet metal in which are formed spaced parallel corrugations 14 of a size and conformation which will snugly receive the semi-cylindrical side of half-round tubing 13, leaving the flat side of the half-round tubing flush with the lands 15 of the shell. In assembling the unit, the lengths of tubing 13 are preferably first held in their relative position and their ends secured through holes 16 in the 20 opposite sides of the header 12, as best illustrated in Fig. 6, and then the shell sheet 11 with the corrugations 14 preformed therein, is bent about the assembled lengths of tubing so that the semi-circular sides of the lengths of tubing 13, which are 25 outward, are received in the semi-cylindrical corrugations 14 as the shell is applied. If desired, and as here shown, the shell 11 may extend beyond the region where the tubing enters the header, being bent in a quarter-cylindrical shape 17 30 to conform to the cylindrical periphery of the header. The two quarter-cylindrical extensions 17 at the respective edges of the shell form a butt joint 18 along the top of the header. The tubing may be held to the shell and the portion 35 17 held to the header by immersing the unit when assembled in a molten metal bath, and the molten metal entering the spaces between the parts will insure an effective heat conducting contact there-between.

40 The unit is supported by brackets 19 bolted to the underside of the top wall of the box and welded to the sides of the shell 11.

Liquid refrigerant passing the float valve from the condenser (neither the condenser nor the 45 float valve being here shown) enters the header 12 at the rear through the tube 20. In the form here shown, each length of tubing 13 forms an independent loop connecting at its ends with the header; but I contemplate that certain features of 50 my invention may be incorporated in evaporators where the tubing is connected in parallel between two headers or where the refrigerant traverses the tubing in series. Gasified refrigerant evaporated within the evaporator is withdrawn through an 55

exhausting or return tube 21 which extends from the rear wall of the header and has its intake opening within a trough 22, the sides of which are so disposed that they constitute baffles for gasified refrigerant bubbling up from the tubes 18 into the header. One end of the trough is supported by a bracket 23 and the other end by the tube 21. Exteriorly of the header 12 the tube 21 is bent downwardly to the bottom of the unit and again upwardly, forming an eye 24 and therebeyond the tube 21 extends upwardly through the top of the box to the intake side of the compressor. The purpose of the arrangement forming the return bend is to provide a trap which will avoid complications if the unit is inverted in transit. I contemplate in the embodiment here shown that the top of the box, from which the cooling unit is suspended, will carry the condenser and compressor on its upper side; the top, together with the cooling unit, condenser and compressor, being removable as a unit from the box.

The previously mentioned inlet tube 20 does not extend directly from the expansion valve but first extends forwardly as a horizontally disposed U-shape 20a on the underside of a shelf 25. The portion 20a is received in a similarly shaped corrugation 25a impressed from the underside of the shelf 25. The portion 20a of the tube may be secured to the underside of the shelf 25 and held in firm heat conducting contact therewith by insertion in a bath of molten metal. A transverse embosture 25b toward the forward edge of the shelf 25 and of substantially the same height as the embossed corrugation 25a, is adapted to support the forward end of the shelf tray 26. Since the tray rests only upon the bead-like upper edges of the embostures 25a and 25b, the area of contact with the tray is minimized, thereby minimizing the area to which the tray can freeze. The shelf may be supported within the unit by depending lateral flanges 27 welded or otherwise secured to the side walls of the shell 11. The use of the inlet tube 20 for refrigerating the shelf 25 avoids the necessity of shunting some of the U-shaped tubing 18 between the lateral walls of the shell 11 at the intermediate height of the shelf. If the latter were done, the side walls of the shell above the shelf would have greater refrigeration than the side walls of the shell below the shelf level. The arrangement as shown also permits the use of the same shell and tubing 18 without any shelf or with two shelves. In the latter instance the shell and tubing remains the same but two shelves 25 are provided and the tubing 20 is formed into a pair of vertically spaced horizontal loops 20a.

I have shown a tray release or lifting jack for the shelf tray 26, which comprises a rod 28 bent to form a transversely journaled shaft portion 29 and a forwardly extending finger or handle portion 30. The shaft portion 29 may be journaled in bearings formed by clips 31 struck from the body of the shelf 25. Intermediate the bearings 31 the shaft portion 29 is offset to provide a lifting crank 32 which is normally stored within a depression 33 formed in the shelf but which, when the handle portion 30 is lifted by the fingers, engages the bottom of the shelf tray 26 and lifts it from the supporting bead corrugations 25a and 25b. The handle portion 30 extends laterally of the side of the shelf tray and between the tray and the adjacent wall of the shelf. A similar tray release 28a is provided on the bottom wall of the shelf 11 for the bottom tray 34. As shown in Figs. 1 and 2, the bottom tray rests directly upon the bottom wall portion of the shell 11 and upon the

upper or flat sides of the half-round tubing 18. In this way the direct contact between the flat bottom of the tray and the flat sides of the tubing affords a direct contact over an extended area for heat conduction from the tray to the refrigerant-carrying tubing. In addition, the flat bottom of the tray is also in intimate contact with the flats of the bottom portions of the shell 11 intermediate the flat sides of the tubing. This gives an additional path for heat conduction from the tray bottom to the tubing.

My arrangement of tubing and shell gives a substantially smooth interior surface for the unit which is easily cleaned and lends itself to direct heat conducting contact with the tray bottom, while corrugations on the exterior present an extended surface area for air convection currents for cooling the box.

While the rear of the shell 11 may, if desired, be closed by a suitable closure plate, I prefer to leave it open as shown, the eye loop 24 of tubing constituting a back stop for the trays. The front and rear edges of the shell 11 are conveniently reinforced by return bends 35. A door 36 is hinged at 37 to one lateral front edge of the shell 11 and is held shut by a friction catch 38 on the other lateral front edge.

If desired, as indicated in the modification of Fig. 7, a false bottom 39 may be provided for the bottom tray 34 upon which the tray release 28a is mounted and which may have upwardly embossed rib-like portions or plateaus as, for example, like those shown for the shelf for minimizing the freezing contact for the bottom of the tray.

This tray release is the subject of my divisional patent application, Ser. No. 113,985, filed December 3, 1936.

While I have thus described these specific embodiments of my invention I contemplate that other changes and substitutions may be made without departing from the scope or spirit of my invention.

I claim:

1. A freezing tray receiving unit for a refrigerating system comprising a sheet metal shell of a generally U-shaped transverse section, an upper header, and lengths of tubing conforming to the shell with their upper ends extending to the header and communicating therewith, the shell having semi-cylindrical corrugations at longitudinally spaced intervals and the tubing being half-round in cross-section with its semi-cylindrical side received in the corrugations and its flat sides facing toward the interior of the shell.

2. A freezing tray receiving unit for a refrigerating system comprising a sheet metal shell of a generally U-shaped transverse section, an upper header, and lengths of tubing conforming to the shell with their upper ends extending to the header and communicating therewith, the shell having semi-cylindrical corrugations at longitudinally spaced intervals and the tubing being half-round in cross-section with its semi-cylindrical side received in the corrugations and its flat sides facing toward the interior of the shell, the shell extending inwardly from its lateral walls to the header to enclose the top of the unit.

3. A freezing tray receiving unit for a refrigerating system comprising a sheet metal shell of a generally U-shaped transverse section, an upper header, and lengths of tubing conforming to the shell with their upper ends extending to the header and communicating therewith, the shell

having semi-cylindrical corrugations at longitudinally spaced intervals and the tubing being half-round in cross section with its semi-cylindrical side received in the corrugations and its flat 5 sides facing toward the interior of the shell; the shell extending inwardly from its lateral walls to the header to enclose the top of the unit and the inner edges of the shell extending further inwardly and conformed to embrace the upper 10 portion of the header.

4. A freezing unit for a refrigerating system comprising a sheet metal shell of a generally U-shaped transverse section, an upper header, and lengths of tubing conforming to the shell with 15 their upper ends extending to the header and communicating therewith, the shell having semi-cylindrical corrugations at longitudinally spaced intervals and the tubing being half-round in cross-section with its semi-cylindrical side received in the corrugations and its flat sides facing 20 toward the interior of the shell, and a freezing tray received in the unit with its bottom resting in direct contact with the flat sides of the tubing.

5. A freezing unit for a refrigerating system comprising a sheet metal shell of a generally U-shaped transverse section, an upper header, and lengths of tubing conforming to the shell with 25 their upper ends extending to the header and communicating therewith, the shell having semi-cylindrical corrugations at longitudinally spaced intervals and the tubing being half-round in cross-section with its semi-cylindrical side received in the corrugations and its flat sides facing 30 toward the interior of the shell, and a freezing tray received in the unit with its bottom resting in direct contact with the flat sides of the tubing and with the bottom wall of the shell intermediate the tubing.

6. A freezing unit for a refrigerating system, comprising an evaporator constructed and arranged to enclose a tray-receiving opening, a shelf at an intermediate height therein, an upper header for the evaporator, and a length of tubing leading to the header and adapted to be connected with a source of condensed refrigerant, and an upwardly embossed bead in the shelf, the 40 length of tubing being received in the groove on the underside of the shelf formed by the embossed bead, for directly refrigerating a freezing tray placed upon the shelf.

50 7. A freezing unit for a refrigerating system, comprising an evaporator constructed and arranged to define an enclosure for freezing trays, a lower freezing tray supported by the evaporator at the bottom of the enclosure, a shelf at an intermediate height in the evaporator and above the lower tray, an upper header for the evaporator, a length of tubing leading to the header and adapted to be connected with a source of

condensed refrigerant, the length of tubing including a reach disposed within the limits of the shelf, substantially in the plane thereof, on the underside thereof, and in heat-conducting contact therewith, and an upper tray having a bottom resting upon the shelf in heat-conducting contact therewith for direct freezing by the said reach, said length of tubing being connected in series with the evaporator whereby refrigerant passes first through the said length of tubing 10 and then through the evaporator.

8. A refrigerated wall for a cooling compartment comprising a metal sheet having a plurality of spaced inwardly facing semi-cylindrical corrugations formed therein and refrigerant-carrying half-round tubing received in the corrugations with the semi-cylindrical side of the tubing fitting the corrugations and in substantial heat conducting contact therewith, and the flat side of the tubing being substantially flush with the 15 flats therebetween whereby the flats constitute heat radiating surfaces for the tubing, the flats and the flat sides of the tubing being exposed to the interior of the compartment.

9. A cooling unit comprising a freezing tray 25 and a shell formed at least in part by a refrigerated wall comprising a metal sheet having a plurality of spaced inwardly facing semi-cylindrical corrugations formed therein and refrigerant-carrying half-round tubing received in the corrugations with the semi-cylindrical side of the tubing fitting the corrugations and in substantial heat conducting contact therewith, and the flat side of the tubing being substantially flush with the 30 flats therebetween whereby the flats constitute heat radiating surfaces for the tubing, the flats and the flat sides of the tubing being exposed to the interior of the compartment.

35 10. A refrigerated wall for a cooling compartment comprising a metal sheet having a plurality of spaced inwardly facing semi-cylindrical corrugations formed therein and refrigerant-carrying half-round tubing received in the corrugations with the semi-cylindrical side of the tubing fitting the corrugations and in substantial heat 40 conducting contact therewith, and the flat side of the tubing being substantially flush with the flats therebetween whereby the flats constitute heat radiating surfaces for the tubing, the flats and the flat sides of the tubing being exposed to the interior of the compartment for directly supporting, and for direct heat conducting contact with, the bottom of the freezing tray.

10. A refrigerated wall for a cooling compartment within the storage compartment of a refrigerator, comprising a metal sheet having a plurality of spaced inwardly facing semi-cylindrical corrugations formed therein and refrigerant-carrying half-round tubing received in the corrugations with the semi-cylindrical side of the tubing fitting the corrugations and in substantial heat 45 conducting contact therewith, and the flat side of the tubing being substantially flush with the flats therebetween, the sheet constituting heat radiating surfaces for the tubing, and the flat sides of the tubing being exposed to the interior of the compartment and the opposite side of the 50 sheet being exposed to air circulating within the storage compartment.

JAMES H. DENNEDY.
